(57) **CLAIM**

The ornamental design for a remote control unit, as shown and described.

DESCRIPTION

FIG. 1 is a perspective view of a remote control unit, showing the new design;

FIG. 2 is a front view thereof;

FIG. 3 is a back view thereof;

FIG. 4 is a first side view thereof; and,

FIG. 5 is a second side view thereof.

The broken lines showing the non-claimed portions of the remote control unit are for illustrative purposes only and form no part of the claimed design.
